(57) **CLAIM**

The ornamental design for a baking pan and closure device combination as shown and described.

DESCRIPTION

1. Baking pan and closure device combination

1.1 is an enlarged perspective view of the closure device of a baking pan and closure device combination; and
1.2 is perspective view of the baking pan and closure device combination.

The features shown in broken lines depict portions of the baking pan and closure device combination that do not form part of the claimed design. The broken line boundary in 1.1 illustrates the detail enlargement and forms no part of the claimed design.

1 Claim, 2 Drawing Sheets

1.2
